THERMIONIC TUBE

Filed March 27, 1928

UNITED STATES PATENT OFFICE

THADDEUS R. GOLDSBOROUGH, OF FOREST HILLS, PENNSYLVANIA, ASSIGNOR TO WESTINGHOUSE ELECTRIC & MANUFACTURING COMPANY, A CORPORATION OF PENNSYLVANIA

THERMIONIC TUBE

Application filed March 27, 1928. Serial No. 265,017.

My invention relates to thermionic devices, and it has particular relation to thermionic amplifier tubes of the equipotential-cathode type.

5 In the patent to Nicolson, No. 1,459,412 is disclosed a thermionic tube having an equipotential cathode comprising an insulating body coated with electron-emissive oxides and provided with an internal heating element for raising the oxides to the temperature at which they become thermionically active. Although the patent discloses the use of a battery for supplying potential to the cathode-heating element, it is now customary 10 in the art to utilize alternating current for this purpose, reliance being placed on the thermal lag in the insulating body to prevent the presence of hum in the output of the tube.

Anode, or plate, potential for tubes of the 15 type to which my invention pertains is usually supplied either from batteries, or from a separate source of rectified alternating current, when such tubes are utilized in radio-receiving apparatus. The use of batteries, or 20 separate rectifiers, while satisfactory in situations where their weight is not objectionable, is not advisable in airplane receivers or transmitters, however, nor in any other situation where both space and weight must be economized.

25 It is, accordingly, one object of my invention to provide a thermionic device which shall require neither batteries nor auxiliary rectifiers for the supply of operating energy thereto.

Another object of my invention is to provide a combined thermionic amplifier tube and rectifier that shall be capable of being entirely energized from a source of com- 30 mercial, or other, frequency alternating current.

Another object of my invention is to provide a combined thermionic amplifier tube and rectifier that shall have incorporated 35 therein means for shielding the amplifier

portion thereof from magnetic effects produced by the rectifier portion.

Another object of my invention is to provide a combined thermionic amplifier tube and rectifier that shall utilize a single heating element for both the amplifier portion and the rectifier portion thereof. 50

Another object of my invention is to provide, in a combined thermionic amplifier tube and rectifier, a rectifier portion that shall utilize a cathode of the equipotential type. 55

Another object of my invention is to provide in a combined thermionic amplifier tube and rectifier, means for controlling the rectifying action of the rectifier portion thereof. 60

Another object of my invention is to provide a device of the aforementioned type that shall be capable of being utilized as a generator of oscillations at any desired frequency, as an amplifier, or as a dectector. 65

Another object of my invention is to provide a device of the aforementioned type that shall be capable of being entirely energized from a source of alternating current of com- 70 mercial, or other, frequency, without the manifestation of objectionable "hum" in the output circuit thereof.

Another, and more specific, object of my invention is to provide a circuit network of 75 a novel type, particularly adapted to connect my combined rectifier-amplifier to a source of alternating current.

A combined thermionic amplifier and rectifier device constructed according to my invention preferably comprises a single cathode-heating element for both the amplifier portion and the rectifier portion thereof. 80 The cathode of the rectifier portion is so constructed and arranged that it, of itself, without other metallic elements intervening, may serve as the anode for the amplifier portion of the device, and has the additional function of shielding the said amplifier portion 85 90

from electromagnetic disturbance from the rectifier portion.

In addition, I have found it distinctly advantageous, though not strictly necessary, to provide means for, in part, neutralizing the space-charge in the rectifier portion. Such means preferably takes the form of a grid-element interposed between the anodes and the cathode constituting the rectifier, in combination with means for impressing any desired bias-potential thereon with reference to the said cathode.

The novel features that I consider characteristic of my invention are set forth with particularity in the appended claims. The invention itself, however, both as to its organization and its method of operation, together with certain further objects and advantages thereof, will best be understood by reference to the following description of a specific embodiment, taken with the accompanying drawing.

The single figure of the drawing is a view in perspective of a preferred form of my combined amplifier-rectifier tube, certain of the elements thereof being broken away to more clearly show the interior structure of the device, together with a diagrammatic view of the circuit network I prefer to employ for energizing the tube when it is utilized in radio reception.

The combined amplifier-rectifier tube comprises an evacuated glass envelope 1 in which an elongated element 2, of porcelain, or the like, is axially mounted. A plurality of openings 3 and 4 extend from end to end of the element 2, through which openings is threaded a loop 5 of resistance wire. The loop 5 is provided with terminals 6 and 7 that extend through the end of the envelope 1, and are connected respectively to the terminals of a secondary winding 8 of a power transformer 10. The primary winding 11 of the transformer may be energized from any convenient source of alternating current.

A cylindrical metallic sheath 12, substantially coextensive with the elongated element 2, and having an enlarged bell-shape lower end 13, is fitted over the said element, and in close contact therewith for the major portion of its length. The exterior surface of the upper portion of the sheath 12 having the lesser diameter is coated with thermionically active oxides, and functions as a cathode with respect to a plurality of cylindrical anodes 14 and 15 which encircle it.

The anodes 14 and 15 are provided with terminals 16 and 17, respectively, which extend through the end of the envelope and are connected to the terminals of a secondary, high potential, winding 18 carried by the power transformer 10.

A grid, or space-charge-controlling, element 20 is disposed intermediate the oxide-coated upper portion of the metallic sheath and the

anodes 14 and 15, and is provided with a terminal 21 which extends through the end of the envelope 1. The grid is connected through a source of biasing potential 22 to an intermediate point 23 on the high-potential secondary winding 18 and, by permitting the partial neutralization of the space-charge, functions to lower the internal impedance of the rectifier portion of the device.

Although the grid 20 is not essential to the operativeness of my combined amplifier-rectifier, it is decidedly advantageous.

A relatively short metallic sheath 24 is disposed around the lower end of the heater element 2 adjacent to the enlarged portion 13 of the long metallic sheath 12, which sheath 24 also carries an exterior coating of thermionically active oxides. The short sheath may, if desirable, be replaced by a metallic film electro-plated on the element 2, or by any other conductive coating in good thermal contact with the said element.

A grid 25 is disposed around the short sheath 24, intermediate it and the enlarged portion 13 of the long sheath 12, and has the usual function of the grid in thermionic amplifier tubes of well-known types.

The long sheath 12, the short sheath 24, and the grid 25 are provided with terminals 26, 27, and 28, respectively, which extend through the lower end of envelope and are conductively connected to corresponding pins 30, 31 and 32 carried by a base member 33 into which the lower end of the envelope is cemented.

An input circuit is provided for the amplifier portion of the device, which circuit, if the device is to function as a combined rectifier and detector, comprises an inductor 34 having a tuning condenser 35 connected in shunt thereto. One end of the inductor is connected through a grid leak 36 and grid condenser 37 to the pin 32, which pin, in turn, is electrically connected to the grid 25. The opposite end of the inductor is connected to the short sheath 24, which constitutes the cathode of the amplifier tube portion.

The input circuit may be coupled to a radiant energy receiving device comprising an antenna 38, a coupling inductor 40, and a ground connection 41.

The output circuit of the amplifier tube portion of the device may be traced from the intermediate point 23 of the secondary winding 18, through a conductor 42 to a filter circuit comprising a plurality of choke coils 43, the primary winding 44 of an output transformer 45, and then through a conductor 46 which is connected to the cathode 24. Each of the choke coils has a bypass condenser 47 connected in shunt thereto, the said condensers having a common terminal which is conductively connected to the pin 30 by way of a conductor 48 and consequently to the elongated sheath member 12.

The secondary winding of the output

transformer 45 may be connected to a pair of telephones 50, as shown, or it may form the input circuit to a second combined rectifier-amplifier device.

5 In the operation of my improved thermionic device the common heating element 2 is energized from the secondary winding 8 and serves to raise the upper end of the elongated sheath member 12 to such a temperature that 10 the oxide coating on the exterior surface thereof emits electrons.

The electrodes 14 and 15, being connected to opposite terminals of the high potential winding 18 constitute a full-wave rectifier 15 with the upper, or cathode, end of the sheath element 12. The space charge between the said electrodes and the cathode may be neutralized to a greater or less extent by adjusting the potential applied to the grid 20 from 20 the biasing source 22. If this potential is made sufficiently positive the impedance of the rectifier portion of the device may be considerably reduced.

The rectified current, which will have a 25 double-frequency component, flows down through the sheath member to the bell shape portion thereof, or to the separate bell shape electrode if such an electrode is utilized, and from it across to the short sheath 24 which 30 constitutes the cathode for the amplifier portion of the device.

The grid 25 in the amplifier portion has the 35 usual and well known function of controlling the flow of space current between the anode and cathode. If, as shown, the device is utilized as a detector, the grid will acquire negative charges dependent upon the size of the grid leak and grid condenser and upon the 40 amplitude of the incoming signals. The operation of the amplifier portion, therefore, differs in no way from the operation of other similar thermionic tubes.

The direct current component of the output current flows back to the midpoint on the 45 high potential secondary winding over the path previously traced, which path includes the primary winding of the output transformer. The 60 cycle and 120 cycle components of the current rectified in the rectifier portion of the device are bypassed back to the secondary winding of the transformer by way of the three condensers 47. The condenser 47 which is connected to the upper 50 terminal of the primary winding 44 of the output transformer 45 serves also to carry the audio frequency component of the output current of the amplifier portion.

The device as shown is accordingly available for use in situations where it is desirable 55 to minimize weight, as, for example, on airplanes and other aerial vehicles. When the device is properly correlated to the circuit network arranged for its energization the 60 amount of hum in the output circuit of the

amplifier portion thereof is substantially negligible.

Although the device has been illustrated as applied to the detection of incoming radio-frequency signals it may, of course, be utilized for their amplification at radio frequencies instead, if desired. 70

By employing a cathode of the equipotential type in both the rectifier and amplifier portions of my improved thermionic device, and by providing sufficient thermal-lag in the insulating supporting element 2 through which the heating wires extend, the hum resulting from varying cathode temperature is materially reduced. 75

In addition, inasmuch as the lower end of the long sheath 12 is interposed between the rectifier and amplifier portions of the device, the said amplifier portion is effectively shielded against magnetic disturbances arising in 80 the rectifier portion. The long sheath, or at least the bell shaped portion thereof, should preferably be made of a magnetic material in order to more effectively serve as a screen. 85

Although I have illustrated and described 90 a specific embodiment of my invention, various modifications thereof and various modifications of the energizing circuits therefor will be apparent to those skilled in the art. My invention is, therefore, not to be limited 95 except insofar as is necessitated by the prior art or by the spirit of the appended claims.

I claim as my invention :

1. A unitary thermionic device comprising 100 an evacuated envelope, elements constituting a rectifier and a radio valve, three of said elements common to said rectifier and said valve, one of said three elements constituting a heater unit and another of said three elements constituting an insulating member surrounding said heater unit. 105

2. A combined thermionic rectifier and amplifier comprising an evacuated envelope enclosing a heating element, a thermionically active element adapted to be heated by said heating element, a plurality of electrodes adapted to cooperate with said active element to constitute a rectifier, and a second thermionically active element adapted to cooperate with said heating element and said first mentioned active element and with a control electrode to constitute a radio valve. 110

3. A combined thermionic rectifier and amplifier comprising an evacuated vessel enclosing a plurality of electrically distinct thermionically active elements, and a plurality of electrodes mounted to cooperate with one of said elements to constitute a rectifier therewith, the last-mentioned element constituting an anode for the amplifier. 115

4. A combined thermionic rectifier and amplifier comprising a plurality of complete triode units, means for shielding the amplifier unit from the rectifier unit, said 120 125 130

shielding means constituting an anode for said amplifier portion.

5. A combined thermionic rectifier and amplifier, including a plurality of thermionically active elements and a plurality of electrodes, a heating device common to said active elements, means adjacent one of said active elements constituting a rectifier therewith, and means for conducting the rectified current to the amplifier portion of the device, said last-named means comprising a shield for preventing inductive interference between the rectifier and the amplifier portion.
- 10 15 In testimony whereof, I have hereunto subscribed my name this 19th day of March, 1928.
THADDEUS R. GOLDSBOROUGH.
